UNITED STATES PATENT OFFICE.

ABE LIPNER, OF INDIANA HARBOR, INDIANA.

TAILOR'S IMPLEMENT.

1,346,832.

Specification of Letters Patent.

Patented July 20, 1920.

Application filed February 17, 1919. Serial No. 277,557.

To all whom it may concern:

Be it known that I, ABE LIPNER, a citizen of the present Government of Russia, residing at Indiana Harbor, in the county of 5 Lake and State of Indiana, have invented new and useful Improvements in Tailors' Implements, of which the following is a specification.

This invention relates to a device adapted 10 to be used by tailors or others for measuring the length of the legs of trousers for the purpose of shortening them, and also to aid the tailor in shortening the trouser legs and in the making of the cuffs at the bottoms 15 thereof.

Among the objects of my invention is to provide a device for the purpose stated, whereby a clerk in a store selling men's ready made clothing may readily and accurately measure the length of the legs of 20 trousers for the customers, without being required to touch the person of the customer, as is necessary when using a yard stick or tape measure for such purpose. A further object of my invention is to provide 25 such a device which may have its parts set or fixed at the length required for shortening the legs of trousers and also which may be used by the tailor or alterer in the work- 30 room in shortening the trousers and in making the cuffs at the bottoms of the legs thereof. A further object of my invention is to provide a device whereby these objects may be accomplished without being required 35 to use chalk in marking on the trousers the length required for shortening and making cuffs, and also to avoid the necessity of basting as well as sewing in folding the material in the making of the cuffs.

40 The invention consists further in the matters hereinafter described and more particularly pointed out in the appended claims.

In the accompanying drawings—

45 Figure 1 is a front elevational view of a tailor's implement constructed in accordance with my invention; the same being shown extended lengthwise to its fullest extent;

50 Fig. 2 is a similar view showing the implement in its closed position;

Fig. 3 is a side elevational view of the 55 device as shown in Fig. 2;

Fig. 4 is an enlarged elevational view of the lower portion of said device and showing the extensible wings thereof in closed 60 positions;

Fig. 5 is a view of the same parts as shown in Fig. 4, with the exception that said wings are shown extended;

Fig. 6 is a horizontal sectional view taken on line 6—6 of Fig. 3;

Fig. 7 is a vertical sectional view taken on line 7—7 of Fig. 4, the view showing the parts at the line of section;

Fig. 8 is a view showing my device in the position it occupies when used for measuring the leg of a pair of trousers when on a person;

Fig. 9 is a view of a pair of trousers turned inside out and illustrating the manner in which my device is used in shortening 75 the leg thereof and forming a cuff thereon at the bottom of the same;

Fig. 10 is a vertical sectional view showing one of the steps in forming a cuff at the bottom of a trouser leg with the aid of my 80 device; and

Fig. 11 is a view showing the cuff complete and the trouser leg turned right side out.

As shown in the drawings, a tailor's implement constructed in accordance with my invention comprises two flat end members 85 10 and 11 and an intermediate member 12, which is in the form of a flat rule rigidly secured by rivets or other fasteners 13, 13 to 90 the end member 11 and from which it extends toward the other end member 10, as shown in Figs. 1 and 8. Said rule 12 has sliding engagement with said end member 10, this being accomplished, in the instance 95 shown, by having the rule 12 extend into an elongated pocket or chamber 14 provided for that purpose in said end member 11, said chamber opening outward through one of the ends of said end member 10 to receive 100 said rule. Said chamber 14 has a length sufficient to receive said rule 12 so that the end member 10 may slide over said rule and be brought into endwise abutting engagement with said end member 11 when 105

said end members are brought together in the closing of the device, as shown in Figs. 2 and 3. By reason of such sliding connection, said end member 10 may be adjusted 5 or moved lengthwise of said rule, for the purpose to be hereinafter described. To clamp the member 10 to said rule 12 in any adjusted position in the length thereof, I provide the rule with an elongated slot 15 10 extending lengthwise of said rule and terminating short of the ends thereof. Said end member 10 is provided with a screw-threaded bolt 16, located adjacent that end of said end member 10 through which the 15 chamber 14 opens. Said bolt 16 extends transversely through the chamber 14 and the side walls 17, 17 thereof and also through the slot 15, as shown in Figs. 1, 2, 3, and 6. The shank of the bolt 16 adjacent 20 its head end is squared, as at 18, and which part extends through one of said side walls 17 to hold said bolt from turning when the thumb nut 19 is applied on the opposed threaded end thereof. Interposed between 25 said thumb nut 19 and the adjacent side wall 17 is a washer 20. The end edge 21 of said member 10 is made V-shaped, as shown in the drawings, in order to fit in a man's crotch.

30 The opposite end member 11 is made in the shape of an inverted T with the rule 12 secured to and extending beyond the shank thereof. Said member 11 comprises two relatively flat side plates, 22, 22, laterally spaced apart to receive therebetween the adjacent end of the rule 12. Said side plates 22, 22 are shaped alike and have the same shape as the end member 11, of which they form a part. Between said plates 22, 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 4 and 5, the shank 24 of the intermediate member 23 has a width less than the shanks of the side plates 22, 22, and to fill the space between the side plates at the sides of said shank 24, I insert side strips 35, 35. The entire device may be made of any material desired, such as light wood, fiber, or the like.

The device herein shown and described is used in the following manner. Take, as an example, the case of a man buying a suit of ready-made clothing. He enters a store dealing in such goods and tries on the trousers 36 (Fig. 8) of the suit he wishes to purchase. The legs 37, 37 of the trousers need shortening in order to fit him, and moreover he wants cuffs made at the bottoms thereof. After the trousers 36 are on the customer, the clerk or tailor, as the case may be, takes my device in closed position (Fig. 2) and places it flatwise against the inseam of the leg of the trousers, with the end member 10 uppermost, as shown in Fig. 8, and its V-shaped edge 21 fitting snugly in the crotch of the customer. Holding the top member 10 in such position, the device is extended by loosening the nut 19 until the lower edge 11^a of the now bottom member 11 reaches the point indicating the length the trouser leg must be for this customer. Then the nut 19 is tightened so as to fix the parts of the device at such length, the latter being accurately indicated by the graduations on the rule 12. For example, suppose that each leg 37 of the trousers, when the bottoms are let out, measure thirty-one inches from the crotch along the inseam, and for the particular customer in question it is necessary to shorten each trouser leg three or more inches. After the clerk or tailor has taken such measure and clamped the parts of the device to such length, the customer removes the trousers and the latter are sent to the work-room for shortening to the extent required. It is the customary practice in the making of men's ready-made clothing to make the trouser legs longer than required and to leave the bottoms let down or unfinished in order to allow for shortening for each customer. Assume further that the particular customer in question desires an inch and one-half cuff at the bottom of each trouser leg 37. This may be provided for by pulling out the rule 32 that distance from the adjacent edge 11^a of the end member 11. This may be done by the clerk at the time the trousers are being measured or fitted on the customer, or may be done by the tailor or alterer from a written order from the clerk after the trousers reach the work-room for alteration. After such measurements have been taken, the customer removes the trousers, and the same are sent to the room for alteration. If desired, the measuring device used by the clerk in each case may be sent to the work-room

with each pair of trousers to be shortened, or the clerk may measure the trousers with a device and send a written order of the alterations to be made with each pair of trousers. Whatever method is followed, the tailor after receiving the trousers, turns them inside out, as shown in Fig. 9. The tailor then inserts one of my devices into one of the legs 37 of the trousers 36 until the end member 10 is in the crotch thereof. It is of course to be understood that the device is extended to the length required for the particular pair of trousers being operated upon from the written order accompanying the same, if the device used by the clerk is not sent with the trousers. The rule 32 is also extended to the length required for the cuff to be made. The device lies along the inseam of the trouser leg 37, and the surplus material 38 extending beyond the end of the rule 32 is turned back, as at 39, over the now outer surface of the leg 37, as shown in Fig. 9. The particular trouser leg 37 is then of a length equal to the length required plus the depth of the cuff. The next step is to turn the folded material 40, which extends beyond the edge 11^a of the end member 11 inward into the spaces between the side plates 22, 22 and the other parts of the device located between said plates, as shown by dotted lines in Fig. 10. Said figure only shows one side of the trouser leg, but it is of course understood that the other side is turned into the space between the associated side plate and the intermediate member 10. The side plates 22, 22 are made flaring and also of a relatively flexible material for that purpose. Such folded material 40 is inserted into such spaces until stopped by the end edge 11^a, whereupon a cuff of the desired height or depth is obtained. When the end of the trouser leg 37 is thus folded, the flap or layer 39 is still on the now outer surface of the trouser leg, and the tailor or workman inserts a strip 41 of "rubber tissue," as it is called in the trade, between said flap 39 and the body part of the leg 37. The wings 27, 27 are extended to the extent permitted by the width across the open end of the trouser leg, so as to hold the cloth taut or distended, and then a hot iron is ironed around the end of said leg so as to press the cuff being formed and to cause the "rubber tissue" 41 to adhere to or bind together the parts of the material between which it is inserted. This completes the shortening of one leg 37 and the making of a cuff at the bottom thereof. After this step has been completed, the other leg 37 is operated upon in the same manner and, when completed, the trousers are turned right side out, with the legs 37, 37 thereof at the required length and cuffs 42 formed as desired, as shown in Fig. 11. If the cus-

5 tomer wishes the bottoms of the legs to be made of a certain "width" or diameter, the wings 27, 27 are extended to the distance required for that purpose and the cloth brought taut above the end of the device.

10 With my improved implement, as described, the measurement may be taken without requiring the clerk or tailor to touch the person of the customer or to place either hand in the latter's crotch, as is always required when either a yard-stick or tape-measure is used for this purpose. Moreover, the measure when taken is accurate, because the end member 10, in having a 15 V-shaped edge 21, fits properly in the crotch of the customer and always enables the measure to be taken from the proper point. The use of marking chalk to designate the length is avoided, and any inexperienced 20 person may take an accurate and proper measure with my device. Furthermore, the trousers may be shortened and the cuffs made by the most inexpert help, as no basting, cutting, sewing, or other expert tailoring 25 work is required. It is not necessary to mark on the material the lengths for such work, and with my device the heretofore time consuming and many stepped method of shortening and making cuffs on trousers 30 is avoided. Other and further advantages of my device will be apparent to those skilled in the art to which my invention appertains.

35 While I have shown and described in detail a device embodying the features of my invention, yet it is to be of course understood that the various details of construction may be changed and modified without departing from the spirit and scope of my 40 invention, and I do not wish to be restricted to the details shown except as pointed out in the annexed claims.

I claim as my invention:

45 1. A device of the character described, comprising two end members, an intermediate member in the form of a rule connected at one end with one of said end members and having endwise sliding engagement with the other of said end members, means 50 for clamping said rule to said last named end member, and a second rule adjustably connected with the first mentioned end member and adapted to be extended endwise beyond that end thereof opposite to the end 55 to which said intermediate rule is connected.

60 2. A device of the character described, comprising two end members, one of which has one edge thereof made substantially V-shaped, an intermediate member in the form 65 of a rule having an elongated slot and connected at one end with one of said end members and having endwise sliding engagement in an elongated chamber provided in the other of said end members, means for clamping said rule to said last named end mem-

ber, consisting of a fastening member extending through said elongated slot and fixed to the said member with which said rule has sliding engagement, and a second rule adjustably connected with the first 70 mentioned end member and adapted to be extended endwise beyond that end thereof opposite to the end to which said intermediate rule is connected.

3. A device of the character described, 75 comprising two end members, an intermediate member in the form of a rule connected at one end with one of said end members and having endwise sliding engagement with the other of said end members, means 80 for clamping said rule to said last named end member, and wings pivoted to said first mentioned end member and adapted to be extended beyond the sides of the same.

4. A device of the character described, 85 comprising two end members, an intermediate member in the form of a rule connected at one end with one of said end members and having endwise sliding engagement with the other of said end members, means for 90 clamping said rule to said last named end member, wings pivoted to said first mentioned end member and adapted to be extended beyond the sides of the same, and arms pivoted to said wings and to each 95 other.

5. A device of the character described, 100 comprising two end members, an intermediate member in the form of a rule connected at one end with one of said end members and having endwise sliding engagement with the other of said end members, means 105 for clamping said rule to said last named end member, wings pivoted to said first mentioned end member and adapted to be extended beyond the sides of the same, arms pivoted to said wings and to each other, and a second rule adjustably connected to the end member to which said wings are connected and adapted to be extended endwise 110 beyond one end thereof.

6. A device of the character described, 115 comprising two end members, one of which has one end edge thereof made substantially V-shaped, an intermediate member in the 120 form of a rule having one end thereof connected with one of said end members and having endwise sliding engagement with the other of said end members, means for clamping said rule to said last named end member, said first mentioned end member having a shank and a cross-part and made of two connected relatively flat side plates laterally spaced apart, a plate located between and connected with said side plates, 125 wings pivoted adjacent the ends of said intermediate plate and adapted to be extended beyond the ends of the cross parts of said side plates, arms pivoted to said wings and to each other, a second rule located between 130

said side plates and extending across said intermediate plate, said second rule being provided with an elongated slot, and a pin secured to said intermediate plate and extending through said slot.

In testimony that I claim the foregoing as my invention, I affix my signature in the

presence of two witnesses, this 13th day of February, A. D. 1919.
